UNITED STATES PATENT OFFICE

HOLMAN HARRY LINN, OF MORRIS, NEW YORK, ASSIGNOR TO THE LINN MANUFACTURING CORPORATION, OF MORRIS, NEW YORK, A CORPORATION OF NEW YORK

HEAD CASTING FOR RADIATORS

Application filed October 8, 1930. Serial No. 487,353.

The invention provides certain improvements in radiators to the end of obviating conditions tending to fouling whereby the maximum cooling area of the radiator is effective at all times.

Radiators, as ordinarily constructed, suffer loss of efficiency after more or less continued use, because the direct flow of the cooling medium, as delivered from the engine, is through the vertical central portion of the radiator with the result that the side portions gradually become choked with sediment, and eventually are completely closed against flow. This puts the burden on the central portion of the radiator with consequent loss of efficiency.

One object of the invention is so to design the radiator that the incoming cooling medium is compelled to flow as well to the side portions as to the central portion, thus insuring full radiation and what is more important taking care of the proper volume of cooling medium.

Another object is the provision of a head casting so designed as to cause proper circulation, the unit casting making for simplicity of manufacture and insuring certainty of operation under all conditions.

The invention is illustrated in the accompanying drawings, in which

Figure 1 is a plan view of a radiator constructed in accordance with the present invention.

Fig. 2 is a rear elevation of the same.

Fig. 3 is a plan view with the upper plate removed.

Fig. 4 is a transverse section through the radiator.

Fig. 5 is an end elevation of the radiator.

Fig. 6 is a fragmentary horizontal view taken upon a center line of the conduits 5 and 6 and showing inlet 4 and outlets 7 and 8.

The improved radiator which may be of usual external design includes an elongated hollow body 1, whereof the bottom wall 2 constitutes the upper header plate from which the usual cooling tubes depend.

In ordinary constructions the flow is centrally of the body and more or less directly to the central tube area. Consequently, under

pump suction, the greater portion of the cooling medium will take the direct path through the central tubes, while appreciably less volume will find its way through the side tubes. Under such conditions the side tubes become choked with sediment and eventually flow through them is cut off.

According to the present invention the rear wall of the body 1 is of heavy section, as at 3, and is formed with a central opening 4 to accommodate the return pipe of the cooling system. Opening 4 is closed against direct communication with the central interior of body 1, but is in direct communication with the side areas through the medium of conduits or channels 5 and 6, ranging through the heavy section rear wall 3 and extending in opposite directions, and in turn communicating with the interior of the body 1, through openings 7 and 8.

The casting 1 is closed at top by a removable shell wall 9 conforming to the shape thereof and equipped with a filling opening 10.

Within the body 1, at each side of the plane of the filling opening, there are integral partitions 11, which are spaced at their lower ends from the header plate 2 throughout the full width of the radiator as at 12. The partitions or baffles 11 are effective to prevent direct full flow of the cooling medium delivered by conduits 5 and 6, from reaching the central portion of the radiator, without, however, menacing sufficient flow to the central portion of the radiator to equalize distribution. Thus, the cooling medium initially is delivered to the side areas of the radiator and compelled, under gravity and pump action, to flow through the tubes at the sides of the radiator, sufficient of the cooling medium being delivered to the central portion of the radiator to maintain a constant and equalized circulation through the tubes leading from the central area. Hence, all of the tubes of the radiator are compelled to take care of their proportionate portion of the cooling medium, and more important, the flow through the tubes at the side portions is such as to insure a constant and complete use of such tubes, and thus obviate condi-

tions making for sediment collection and eventual fouling of the tubes.

The essential and characteristic feature of the invention is the provision of the side delivery conduits in a unit head casting, thus insuring the proper relation of such conduits, maintaining them as integral and fixed parts of the radiator construction, and preventing the possibility of displacement and avoiding the use of independent pipes and connections otherwise necessary.

The radiator may or may not be provided with an overflow pipe 13.

Having described the invention, what is claimed is:

15. 1. A radiator including an upper header section having a rear wall of relatively heavy section formed with an inlet, and conduits formed in said wall and establishing communication between said inlet and the side regions of the header.
20. 2. A radiator including a hollow body forming an upper header, the rear wall of the body being thickened and formed with an inlet closed against direct communication with the central interior region of the body, said wall having integral conduits extending from the inlet and communicating with the side regions of the body, and partitions on each side of said central region effective to provide for restricted communication between the side and said central regions of the body.
25. 3. A radiator including a hollow body forming a header, one longitudinal wall of such body being formed with a central inlet and with conduits extending longitudinally of and wholly within said wall, said conduits opening into the interior of the body in both directions beyond said inlet, said central inlet and conduits being otherwise closed from communication with said header.
30. 4. A radiator including a hollow body forming a header, one longitudinal wall of such body being formed with a central inlet and with longitudinally ranging conduits open to such inlet at one end, the opposite ends of the conduits opening into the body between the ends of the body and such inlet, and means within the body to restrict free flow between said conduits and the central portion of the body.

In testimony whereof I affix my signature.
HOLMAN HARRY LINN.
